[57] CLAIM

The ornamental design for a vertebra for a recreational vehicle and mobile home hose support, as shown and described.

DESCRIPTION

FIG. 1 is an end elevational view of a vertebra for recreational vehicle and mobile home hose support showing my new design.

FIG. 2 is a side elevational view thereof, and FIG. 3 is a top plan view thereof.

The undisclosed side and bottom of the vertebra are understood to be mirror images of the side and top shown in FIGS. 2 and 3 respectively.

FIG. 1

FIG. 2

FIG. 3
